UNITED STATES PATENT OFFICE.

CHARLES FREDRICK BUTTERWORTH, OF TROY, NEW YORK.

SLEEVE FOR COATS.

SPECIFICATION forming part of Letters Patent No. 296,130, dated April 1, 1884.

Application filed March 16, 1883. (No model.)

To all whom it may concern:

Be it known that I, CHARLES F. BUTTERWORTH, of Troy, in the county of Rensselaer and State of New York, have invented a new and useful Improvement in the Sleeves of Coats and other like Garments, of which the following is a full, clear, and exact description.

The object of my invention is to provide a close, warm, and elastic fit for the sleeve of a coat or other like garment about the wrist of the wearer; and to this end the invention consists in the peculiar construction and arrangement of parts, as hereinafter fully described, and pointed out in the claim.

Reference is to be had to the accompanying drawings, forming part of this specification, in which similar letters of reference indicate corresponding parts in both the figures.

20 Figure 1 represents a longitudinal section of the outer or hand end portion of a coat-sleeve with attached wristlet in accordance with my invention, and Fig. 2 a partly broken or sectional face view of the wristlet detached.

25 A in the drawings indicates the outer or turned-in portion of a coat-sleeve, and b its lining. C is the wristlet, arranged on the inside of the sleeve, at some little distance from the outer end of the sleeve, and constructed to 30 form a hollow fur band of annular shape, with a metal, rubber, or other spring, d, within it. Such elastic wristlet is attached to the coat-sleeve by a strip, e, of cloth or other material, stitched on its one edge, as at f, to the wristlet, and united at its opposite edge (interposed 35 between the outer material of the sleeve and its lining b) by a row of stitching, h, arranged to pass through it and through the sleeve and its lining. By thus indirectly attaching the 40 wristlet to the sleeve the hand is prevented from catching in the exposed end of the lining, or from puckering it when drawing the sleeve, with its attached wristlet, on or off.

Instead of arranging the wristlet within the sleeve at some little distance from its outer end, it might be arranged at the extreme end thereof. In either case, however, it projects inward transversely to the sleeve, and is a permanent attachment thereto in close connection with the sleeve, so that no cold air can pass up between it and the sleeve, while its elastic construction causes it to closely hug the wrist without restricting the free motion of the hand, all of which will be found very conducive to comfort in driving during cold weather.

I am aware that muffs have been formed or provided with elastic fur bands at the ends of the openings through them, but such muffs are separate articles to be worn by or held by the hands, which are accordingly prevented from being otherwise used, and they form no part of a garment fitting the person; and I am also aware that sleeves and oversleeves have been provided with attachments at their lower ends having elastic in them, to cause them to fit closely around the wrist to exclude the air, and I therefore do not claim such inventions; but

What I do claim, and desire to secure by Letters Patent, is—

The combination, with an ordinary coat-sleeve, of the elastic wristlet C, consisting of a hollow annular fur band and a spring, d, within it, and the securing-strip e, having one edge secured to the wristlet and its other edge interposed between the turned-in portion of the sleeve and its lining, and the whole secured together and to the outer portion of the sleeve, substantially as herein shown and described.

CHARLES FREDRICK BUTTERWORTH.
